TRAIL MOWER

George B. Hill, Celina, Ohio, and Melvin J. Happe,
 New Holland, Pa., assignors to New Holland
 Machine Division of The Sperry Corporation,
 New Holland, Pa., a corporation of Delaware

Application February 1, 1951, Serial No. 14,062

Term of patent 7 years

(Cl. D40—1)

To all whom it may concern:

Be it known that we, George B. Hill and Melvin J. Happe, citizens of the United States, residing at Celina, county of Mercer, State of Ohio, and New Holland, State of Pennsylvania, respectively, have invented a new, original, and ornamental design for Trail Mower, of which the following is a specification, reference being had to the accompanying drawing, forming a part hereof.

Figure 1 is a side perspective view of a trail mower showing our new design.

Figure 2 is a top plan view of the trail mower.

The broken line portions of the drawing are shown for illustrative purposes only.

We claim:

The ornamental design for a trail mower, as shown and described.

GEORGE B. HILL.
 MELVIN J. HAPPE.
